(57) **CLAIM**

The ornamental design for a plastic container, as shown and described.

DESCRIPTION

FIG. 1 is a top, front, and right side perspective view of the plastic container;

FIG. 2 is a left side elevational view thereof;

FIG. 3 is a right side elevational view thereof:

FIG. 4 is a bottom plan view thereof, shown as unclaimed environment;

FIG. 5 is a bottom plan view thereof, shown as an alternate unclaimed environment; and

FIG. 6 is a top plan view thereof.

The dash-dot-dash-dot-dash broken lines shown in the drawings define the boundaries of the claimed design. The dash-dash-dash-dash broken lines shown in the drawings are for environmental purposes only and form no part of the claimed design.
